MACHINE FOR AUTOMATICALLY PRODUCING APPAREL BELTS AND LIKE STRAP BODIES

James Allen Tuck, Philadelphia, Pa., assignor, by mesne assignments, to Louis Krantz, New York, N. Y.

Application March 16, 1951, Serial No. 216,077

6 Claims. (Cl. 69—1)

1

This invention relates to an automatic machine for producing apparel belt and like strap bodies from strip stock ready for the reception of buckles by which the same are equipped for use.

The instant invention has for an object to provide an automatic machine through which stock strips can be passed and processed to effect the different operations required to form the same into belt or strap bodies ready for application of buckles thereto whereby to provide finished belts or straps; such operations generally including (1) beveling or trimming the edges of the stock strips; (2) punching the stock strips to provide buckle reception slots and suitably spaced buckle tongue engageable holes, and cutting the stock strips to shape the buckle attachment and free ends of the belt or strap bodies; (3) skiving the stock strips; (4) embossing or scoring the face surface of the stock strips or belt or strap bodies; and (5) stamping the belt or strap bodies with size and suitable descriptive or other indicia.

The invention has for a further object to provide an automatic machine for the stated purposes which is arranged to provide mechanisms for performing the above specified operations respectively at different stations, means being provided for automatically successively moving the stock strips from station to station for the performance of said operations in sequence.

Another object of the invention is to provide improved mechanisms for performing the several individual operations above specified, including means for holding the stock strips immovable, when necessary, in proper position in relation to said operating mechanisms subject to the operations thereof.

Still another object of the invention is to provide an automatic machine for the stated purposes which can be quickly and easily adjusted to accommodate its operating mechanisms for performance upon stock strips according to width and length sizes of finished belt or strap bodies desired to be produced.

Other objects of this invention, not at this time more particularly enumerated, will be understood from the following detailed description of the same.

An illustrative embodiment of the machine according to this invention is shown in the accompanying drawings, in which:

Fig. 1 is a top plan view of the belt or strap body producing machine; and Fig. 2 is a longitudinal sectional view of the same, taken on line 2—2 in Fig. 1.

Fig. 3 is a fragmentary longitudinal vertical

section through the stock strip cutting and punching mechanism of the machine, taken on line 3—3 in Fig. 1, but drawn on an enlarged scale; Fig. 4 is an enlarged detail plan view of means associated with the cutting and punching mechanism and operative to center a stock strip in alignment with said cutting and punching mechanism subject to the operation thereof, this view showing the normal initial position of said centering means; and Fig. 5 is a view similar to that of Fig. 4, but showing the operative position of said centering means.

Fig. 6 is a fragmentary longitudinal vertical section through the stock strip skiving mechanism of the machine, taken on line 6—6 in Fig. 1, but drawn on an enlarged scale; Fig. 7 is a similar view in part showing the skiving instrumentality in performance of its operative skiving stroke.

Fig. 8 is a fragmentary transverse vertical section, taken on line 8—8 in Fig. 1 but drawn on an enlarged scale, to show means for stamping the work with size, descriptive or other indicia.

Fig. 9 is a fragmentary transverse vertical section, taken on line 9—9 in Fig. 1 but drawn on an enlarged scale, the same showing transfer means on its forward stroke operative to transfer the work from one operating mechanism of the machine to another; Fig. 10 is a similar view showing said transfer means on its retractive stroke; Fig. 11 is a detail cross-sectional view, taken on line 11—11 in Fig. 9; Fig. 12 is another detail cross-sectional view, taken on line 12—12 in Fig. 9; and Fig. 13 is still another cross-sectional view, taken on line 13—13 in Fig. 9; all of said cross-sectional views being drawn on a further enlarged scale.

Fig. 14 is a fragmentary transverse vertical section, taken on line 14—14 in Fig. 1 but drawn on an enlarged scale, the same showing the belt or strap body discharge mechanism of the machine in a form also adapted to score or crease the face of the belt or strap body, together with the means for operating the same; and Fig. 15 is a fragmentary vertical longitudinal section of the same, taken on line 15—15 in Fig. 14.

Similar characters of reference are employed in the hereinabove described views, to indicate corresponding parts.

Referring to the drawings, the framework of the machine, in the illustrative embodiment thereof as shown, is formed by spaced apart stationary transverse frame members 1 and 2 at one end thereof, a similar stationary transverse frame member 3 at the opposite end thereof, and a movable transverse frame member 4 intermediate said

end frame members. The stationary end frame members are joined together by side rails 5. Respectively supported by the stationary frame members 1, 2 and 3 are respective transverse frame plates or aprons 6, 7 and 8. Supported by the movable frame member 4 are similar frame plates or aprons 9 and 10. Supported by the frame members 1 and 2 above their frame plates or aprons 6 and 7 is a fixed horizontal work table 11, and similarly supported by the movable frame member 4 and its frame plates or aprons 9 and 10 is a work table section 12 which is thus carried by and so as to be movable with said movable frame member 4. At the receiving end of the machine is mounted a table extension 13 which is disposed in the plane of the work table 11 for communication therewith. Said table extension 13 is supported at its outer end by an additional stationary frame member 14 which includes a transverse frame plate or apron 15.

The main shaft 16 of the machine extends longitudinally thereof beneath the work table parts 11, 12 and 13, the same being journaled in bearings 17 respectively affixed to frame plate or apron parts of the machine framework. Power may be transmitted to said main shaft 16 from any suitable source; preferably, however, an electric motor M is provided to serve as a power source. Power is transmitted from the motor M to the input shaft 18 of a reduction gear mechanism 19, and by the latter, through gearing 20, to said main shaft 16.

A pair of stock strip feed rolls is provided in connection with the work table 11 and its extension 13 (see Figs. 1 and 2). These feed rolls comprise a lower roll 21, the shaft of which is journaled in bearings 22 mounted in connection with the stationary frame member 1 of the machine framework, and an upper roll 23. The shaft of the upper roll 23 is journaled in a bearing 24 carried by carrier arms 25 which are pivotally connected with supporting means 26 mounted in connection with the stationary frame member 1 of the machine framework. As thus supported, the upper feed roll 23 can be adjusted relative to the lower feed roll 21, by means of adjusting screw 27, whereby to accommodate the nip of said feed rolls to stock strips of different thickness. The means for driving the feed rolls 21 and 23 comprises a transverse countershaft 28 which is driven from the input shaft 18 of the reduction gear mechanism 19 by a chain and sprocket transmission 29. The feed rolls 21 and 23 are driven in opposite directions from the countershaft 28 by a chain and sprocket transmission 30 (see Fig. 2).

Mounted on the table extension 13, adjacent to its outer end, is a stock strip edge beveling or trimming means, in advance of which are mounted laterally spaced guide members 31 which lead a stock strip to and for passage through said edge beveling or trimming means, when said stock strip is introduced into the machine for passage therethrough. The edge beveling and trimming means comprises a pair of laterally spaced and opposed carrier plates 32 which respectively border opposite sides of the path of movement of a stock strip into the machine. Supported by said carrier plates 32 are cutting knives 33, the forward ends of which terminate in sharp, chisel-like cutting edges which are positioned close to the discharge side of the nip of a pair of drive rollers by which the stock strip is advanced to move its edges into engagement with the cutting knives subject to the edge beveling or trimming action thereof. Said drive rollers comprise a

lower rollers 34 and an upper roller 35, the shafts of which are journaled in bearings similar to those which journal the shafts of the feed rolls 21 and 23 as above described. The lower drive roller 34 is driven from the shaft of the lower feed roll 21 by sprocket and chain transmission 36, and similarly the upper drive roller 35 is driven from the shaft of the upper feed roll 23 by sprocket and chain transmission 37 (see Fig. 2). It will be understood, however, that said drive rollers may be power driven in any other manner found convenient or desirable, the above described power transmission thereto being merely illustrative. Supported from and above the table extension 13 is a transverse frame 38 having bearing arms 39 extending therefrom. Journaled in and between said bearing arms is a transverse adjusting shaft 40, to one end of which is affixed a hand wheel 41 by which it can be manipulated. This adjusting shaft 40 is provided with a left hand screw-threaded section and a right hand screw-threaded section. The carrier plates 32 are respectively supported by brackets 42 which are respectively in threaded engagement with the respective left and right hand screw-threaded sections of the adjusting shaft 40, whereby, upon manipulation of the latter, the carrier plates 32 can be adjusted toward and from one another to accommodate their cutting knives 33 for engagement with different widths of stock strips (see Fig. 1).

Mounted on the table extension 13, to extend intermediate the stock strip beveling or trimming means and the feed rolls 21 and 23, is a stock strip guiding means 43, which is laterally adjustable to accommodate stock strips of different widths. Said guiding means 43 guides a stock strip issuing from the beveling or trimming means to the feed rolls 21-23, so that the same will be engaged by the latter and thereby advanced onto the work table 11-12 subject to movement by transfer mechanism, to be later described, from one station to another at which various processing operations are performed by mechanisms hereinafter described.

As a stock strip issues from the feed rolls 21-23 it is lodged upon the rearward part of the work table 11-12, which constitutes a receiving station, in longitudinal extension over the latter, and so as to be held against outward lateral displacement by back stop elements 44 which are fixed upon the work table.

Laterally spaced apart at respective stations between the rearward and forward sides of the work table are various mechanisms by which the stock strips are processed to finally produce finished apparel belt or strap bodies. In the illustrative embodiment of the machine as shown, first beyond the receiving station is the station at which is located the mechanism for punching and end shaping the stock strips; next beyond the punching and end shaping station is the station at which is located the mechanism for skiving the stock strips to complete formation of the buckle receiving end of the produced belt or strap; next beyond the skiving station is the station at which is located the mechanism for stamping or imprinting the stock strip with belt or strap size, descriptive or other desired indicia; and beyond the latter station is the belt or strap body discharge station, in connection with which mechanism for embossing or scoring the front face surface of the produced belt or strap may be associated. It will be understood that the described and shown sequence of sta-

tion relationship maybe varied; i. e. the sequential order in which the performance of the several operations involved takes place may be changed, if desired, to give relative precedence of one given operation over another.

The means for punching and end shaping the stock strips, in a preferred form and arrangement thereof as shown more particularly in Figs. 1, 3, 4 and 5, comprises mechanism which is operative upon the rear end portion of a stock strip for shaping and slotting the buckle receiving end of a belt or strap body, this mechanism being mounted in connection with the stationary frame member 1, and mechanism operative upon the forward end portion of a stock strip for shaping and punching the free end part of a belt or strap body, the latter mechanism being mounted in connection with the movable frame member 4 in longitudinal alignment with the buckle end shaping and slotting mechanism, subject, by movement of the movable frame member 4, to adjusted spaced relation to the latter mechanism according to length of belt or strap body to be produced, in manner and by means herein subsequently explained.

In Fig. 1 the buckle end shaping and slotting mechanism is generally indicated by the reference character 50 and the free end shaping and punching mechanism is generally indicated by the reference character 51.

The buckle end shaping and slotting mechanism 50 is best shown in Fig. 3, and comprises a vertically reciprocable carrier frame, generally indicated by the reference character 52 and formed by laterally spaced C-shaped side plates 52' which straddle the outer end of the work table 11. The upper end of said carrier frame 52 is provided with top cross-heads 53 and 53', and its lower end with a bottom cross-head 54, the latter having a dependent slide arm 55 which is slidably supported in a bottom guide member 56 that is mounted on the frame plate or apron 6 of frame member 1 below the work table 11. Mounted on the top end of the frame member 1, which projects above the work table 11, is a top guide member 57. Extending upwardly, through the top cross-heads 53—53' is an upper slide arm 58 which is slidably supported by the top guide member 57. Affixed to the lower end of the slide arm 58 below the cross-head 53' is a carrier body 59 which carries a tool holder 60. The tool holder 60 can be longitudinally adjusted relative to the carrier body 59 by an adjusting screw 61 which has swivel connection with the tool holder 60 and which is in threaded connection with a nut piece 62 dependent from an end of the carrier body 59. Mounted on the tool holder 60 is a suitably shaped cutter member or blade 63 which operates to shape the extremity of the buckle attachment end of the belt or strap body to be produced. Also mounted on the tool holder 60 is a slotting punch 64 which operates to form the buckle attachment slot in the belt or strap body to be produced. The carrier body 59 with the tool holder 60 can be vertically adjusted within the carrier frame 52, whereby to predetermine the spacing of the cutting blade 63 and slotting punch 64 relative to the work table 11 according to the stroke amplitude of carrier frame reciprocation. To this end, adjusting screws 65 are threaded through the cross-head 53' and are operative to engage the carrier body 59 so as to vertically adjust its position and thereby the tool holder and tools in the carrier frame.

Carried by the tool holder 60 is a punch scrap discharge duct 66 with which the slotting punch 64 communicates so that punch scrap will pass from the interior of the latter into said discharge duct; injector means 67 being connected with the duct for delivering compressed air thereinto whereby to convey the punch scrap therethrough to a suitable point of discharge and collection.

The means for effecting properly timed reciprocation of the carrier frame 52, and the tools operated thereby, comprises a lay shaft 68 which extends longitudinally beneath the table parts 11 and 12. This lay shaft is journaled in bearings 69 respectively mounted on frame plate or apron parts of the machine framework. The lay shaft 68 is driven from the main shaft 16 by means of a drive gear 70 on the latter which meshes with a driven gear 71 on the former. Journaled in the bottom cross-bar 54 of the carrier frame 52 is an anti-friction roller 72, and fixed on the lay shaft 68 is an actuating cam 73 which engages said roller 72, and which functions to reciprocate the carrier frame 52 and the tools carried thereby. Spring means 74 operates to cause the carrier frame and its roller 72 to follow the cam 73, thus assuring operative reciprocation of said carrier frame and the tools carried thereby.

The mechanism 51 for shaping and punching the free end portion of the producing belt or strap bodies, which mechanism is longitudinally aligned with the above described buckle end shaping and slotting mechanism, and adapted to be simultaneously operated with the latter at the same table station, is also best shown in Fig. 3, and likewise comprises a vertically reciprocable carrier frame generally indicated by the reference character 75 and formed by laterally spaced C-shaped side plates 75' which straddle the outer end of the work table section 12 associated with the movable frame member 4. The upper end of carrier frame 75 is provided with top cross-heads 76 and 76', and its lower end with a bottom cross-head 77, the latter having a dependent side arm 78 which is slidably supported in a bottom guide member 79 that is mounted on a frame plate or apron 10 of the movable frame member 4 below the work table section 12. Mounted on the top end of the movable frame member 4, which projects above the work table section 12, is a top guide member 80. Extending upwardly through the top cross-heads 76 and 76' is an upper slide arm 81 which is slidably supported by said top guide member 80. Affixed to the lower end of said slide arm 81 below the cross-head 76' is a carrier body 82 which carries a tool holder 83. The tool holder 83 can be longitudinally adjusted relative to the carrier body 82 by an adjusting screw 84 which has a swivel connection with the tool holder 83 and which is in threaded connection with a nut piece 85 dependent from an end of the carrier body 82. Mounted on the tool holder 83 is a suitably shaped cutter member or blade 86 which operates to point the extremity of the free end portion of the belt or strap body to be produced. Also mounted on the tool holder 83 are a plurality of longitudinally spaced hole punches 87 which operate to form buckle tongue engageable perforations or holes in the free end portion of the belt or strap body to be produced. The carrier body 82 can be vertically adjusted within the carrier frame 75, whereby to predetermine the spacing of the cutting blade 86

and punches 87 relative to the work table section 12 according to the stroke amplitude of the carrier frame reciprocation. To this end, adjusting screws 88 are threaded through the cross-head 76 and are operative to engage the carrier body 82 so as to vertically adjust its position and thereby the tool holder and tools in the carrier frame.

Carried by the tool holder 83 is a punch scrap discharge duct 89 with which the punches 87 communicate so that punch scrap will pass from the interiors of said punches into said discharge duct; injector means 90 being connected with the duct 89 for delivering compressed air thereto whereby to convey the punch scrap therethrough to a suitable point of discharge and collection.

The means for reciprocating the carrier frame 15, and the tools operated thereby, simultaneously with the reciprocation of the carrier frame 12 and the tools carried thereby comprises a cam 91 also mounted on the lay shaft 68. This cam 91 engages an anti-friction roller 92 which is journaled in connection with the bottom cross-head 17 of the carrier frame 15. Spring means 93 causes the carrier frame 15 and its roller 92 to follow the cam 91, thus assuring timed operative reciprocation of said carrier frame 15 and the cutting blade 86 and punches 87 carried thereby.

Cooperative with the respective above described stock strip cutting and punching mechanisms are centering devices which are adapted to respectively engage the opposite ends of a stock strip which has been advanced over the work table and delivered beneath said mechanisms to receive processing thereby. These stock strip centering devices, by their operations, which are timed to take place prior to operative strokes of the cutting and punching mechanisms, automatically engage the respective end portions of the delivered stock strip so as to shift said stock strip and bring it into accurately centered, longitudinally aligned relation to the cutting and punching tools, whereby to assure that the cuts and perforations produced by the latter are accurately located and aligned midway between the side margins of said stock strip. These stock strip centering devices are respectively disposed to extend from the worktable sections 11 and 12 for cooperation therewith, and are generally indicated in Fig. 1 by the reference character 100. Since both said centering devices are alike and are subject to properly timed operation by like actuating means, detail description of one will suffice, reference being had more particularly to the showing thereof in Figs. 3, 4 and 5.

Each centering device comprises a longitudinal slideway member 101 which is suitably supported for extension from the work table section with which it is associated in the plane thereof. Slidably movable in said slideway member 101, toward and from the cutting and punching mechanism with which it is aligned, is a slide plate 102. Pivottally mounted on the forward end portion of the slide plate 102 are a pair of laterally spaced gripper fingers 103, the free end portions of which project freely beyond the forward end of the slide plate, so as to overhang the work table surface. The free end portions of the gripper fingers 103 terminate in gripping jaws 104 which project from the undersides thereof so as to abut the work table surface. Mounted in guide members 105, which are affixed on the top of the slide plate 102, is a relatively slidable longitudinal draw-bar 106, which is dis-

posed centrally between the gripper fingers 103. Pivottally connected with the forward end portion of the draw-bar 106 are a pair of links 107, the outer ends of which are respectively pivotally coupled with the respective gripper fingers 103 at points intermediate the ends thereof. A pull-spring 108 is interconnected between the slide plate 102 and the draw-bar 106, whereby to yieldably hold the latter advanced on the former in position to transmit thrust through the links 107 to the gripper fingers 103, thus normally spreading apart said gripper fingers, and thereby disposing the same in normal initial out swung or open positions shown in Fig. 4. Extending rearwardly from the draw-bar 106 is a drag rod 109, which slidably extends through an upstanding, transverse abutment flange 110 with which the outer end of the slideway member 101 is provided. Mounted on the outer end of said drag rod 109 is a spring cushioned stop means 111. Means is provided to cause timed reciprocation of the slide plate 102 whereby to operate the centering device. This means comprises an actuating lever 112 the pivotal shaft 113 of which is supported by a bracket arm 114 that is secured to and extends from an adjacent frame plate or apron of the machine framework. The upper end of said actuating lever 112 is connected by a link 115 with the slide plate 102. Timed oscillation of the actuating lever 112 is produced by a cam 116 that is mounted on the main shaft 16 of the machine, and which is engaged by the anti-friction roller 117 of a crank arm 118 mounted on the pivoting shaft 113 of said actuating lever 112. Spring means 119 is provided to cause the crank arm 118 to follow the cam 116.

In the operation of the centering devices, after a stock strip has been moved over the work table and positioned beneath the cutting and punching mechanisms, before operative stroke of the latter, the cams 116 operate to swing inward the actuating levers 112, thereby moving inwardly, on the slideway members 101, the slide plates 102. As the slide plates move inward, the drag rods 109 move inwardly therewith until the spring cushioned stop means 111 engage the abutment flanges 110, thus arresting further inward movement of the draw-bars 106 while the slide plates 102 complete their forward movements. As a result of this, draft is exerted through the links 107 upon the gripper fingers 103, whereby the latter are inswung so that their gripping jaws 104 engage opposite sides of the stock strip, thereby to shift and hold the latter in properly centered and aligned relation to the cutting and punching mechanisms, while the latter perform their functions (see Figs. 1 and 5). The operation of the centering devices is so timed by their actuating cams 116 that after operation of the cutting and punching mechanisms is accomplished and said mechanisms return to normal initial positions, the slide plates 102 are retracted, the draw-bars 106 are released from restraint by the stopped drag rods 109, so that the pull-spring 108 can again function to exert forward pressure on the draw-bars 106, whereby to exert outward thrust through the links 107 upon the gripper fingers 103, and thus return the latter to their normal initial out swung or open positions (see Fig. 4).

The means for skiving the stock strip in the area of the buckle attachment slot formed therein, whereby to facilitate folding of the produced belt or strap body in said area about a bar of

a buckle to be subsequently attached thereto, is preferably located at a next succeeding station after that at which the stock strip cutting and punching mechanisms are stationed. Said skiving means is generally indicated in Fig. 1 by the reference character 120 and the stock strip clamping means which is cooperative therewith by the reference character 121.

The skiving means is best shown in Figs. 6 and 7, and comprises a slideway member 122 which extends outwardly from the work table 11 in the plane thereof. Longitudinally slideable in said slideway member is a slide plate 123. Carried by the slide plate, to overhang a transverse opening 124 with which its inner end portion is provided, is a skiving blade 125, the latter being disposed with its cutting edge directed toward the outer end of the slide plate. Mounted in upstanding bearings 126 in connection with the outer end portion of the slide plate 123 is a bell-crank lever comprising a substantially vertical arm 127, which extends downwardly through an opening 128 in the outer end portion of the slide plate 123, and a substantially horizontal arm 129 which extends inwardly over the slide plate 123 to overhang the skiving blade 125 and the bordering opening 124 in said slide plate. Mounted on the free inner end of said bell-crank arm 129 is a pressure roller 130. The outer end portion of the slide plate 123 is provided with longitudinally spaced dependent lugs 131 and 132 in which are respectively mounted adjustable stop screws 133 and 134 to oppose opposite sides or faces of the bell-crank arm 127 which depends therebetween.

The means for reciprocating the slide plate 123 to effect the skiving operation comprises the following mechanism. Journaled in bearings 135 mounted on frame plates or aprons of the machine framework is another longitudinal lay shaft 136, the same being driven from the gear 71 on the lay shaft 68 by a driven gear 137 which is fixed on said lay shaft 136. Driven by said lay shaft 136 is a cam 138 which effects timed operation of a lever means 139. Said lever means 139 is pivoted on a bracket arm 140 that extends from the frame plate or apron 7 on the frame member 2 of the machine framework. A connecting rod or link 141 is connected between the lever means 139 and the arm 127 of the bell-crank lever carried by the slide plate 123. Pull spring means 142 causes the lever means 139 to follow the actuating cam 138.

Means is provided for clamping a stock strip to the work table against longitudinal movement during the skiving operation. Said clamping means may be varied in form and location. One illustrative arrangement and location thereof, as shown, is generally indicated by the reference character 121, and is best shown in Fig. 6, the same comprising a carrier frame 144 which is formed by laterally spaced side plates 144' which straddle the outer end of the work table section 12. The upper end of this carrier frame is provided with a cross-head 145. Slidably extending upwardly through said cross-head 145 is a slide arm 146, the upper free end portion of which is slidably supported by a guide member 147 that is mounted on the top end of the movable frame member 4 which projects above the work table section 12. Fixed on the lower end of said slide arm 146 is a clamp plate 148 that is opposed to the surface of said work table section 12. A compression spring 149 is mounted around the lower end portion of the slide arm 146 inter-

mediate the cross-head 145 and said clamp plate 148, and is operative to yieldably cushion the clamp plate in its normally stopped position as determined by a stop collar 150 that is fixed on the upper end portion of the slide arm 146 to normally abut the upper end of said cross-head 145. The lower end of the carrier frame 144 is provided with a bottom cross-head 151, the same having a dependent slide arm 152 which is slidably supported in a bottom guide member 153 that is mounted on a frame plate or apron of the movable frame member 4 below the work table section 12.

The means for effecting properly timed reciprocation of the carriage frame 144 and clamp means carried thereby comprises an actuating cam 154 that is fixed on the lay shaft 136. This cam 154 engages an anti-friction roller 155 which is mounted in connection with the bottom cross-head 151. Spring means 156 operates to cause the carrier frame 144 and said roller 155 to follow the cam 154, thus assuring operative reciprocation of the carrier frame and clamp means.

In the operation of the skiving means, after a stock strip has been advanced over the work table so as to be aligned with the skiving device and cooperative clamp means, the cam 154 is timed to lower the carrier frame 144, whereby to bring the spring cushioned clamp plate 148 down upon the underlying stock strip, thus clamping the latter to the work table against longitudinal shift under the pull of the actuated skiving device. The stock strip being thus clamped to the work table, the cam 138 is timed to cause an outward working movement of the slide plate 123 and skiving blade 125 carried thereby. Preparatory to this working movement, the cam actuated outward thrust of the link 141 against the arm 127 of the bell-crank lever carried by the slide plate 123, causes this arm 127 to swing outward against the stop screw 133, thereby down swinging the horizontal bell-crank lever arm 129 so as to force the pressure roller 130 down upon the underlying stock strip, whereby to press the underside of the latter against the cutting edge of the skiving blade 125 (see Fig. 7). This having taken place, continued outward thrust of the link 141 is transmitted, through the engaged bell-crank lever arm 127 and stop screw 133, to the slide plate 123, so as to slide the latter outwardly on the slideway member 122, and thereby to cause the skiving blade 125 to shave or skive the underface of the engaged portion of the stock strip, whereby to thin such portion. Upon completion of the skiving stroke, the actuating cam 154 operates to first up swing the bell-crank lever so as to lift the pressure roller 130 away from the stock strip, and thereupon to retract the slide plate and skiving blade to normal initial position, and to uplift the carrier frame 144 so as to release the stock strip from the clamp plate 148.

Located at a next succeeding station after that at which the skiving means is stationed is the means for stamping or imprinting a belt or strap body being produced with size, descriptive or other desired indicia. This stamping means is generally indicated in Fig. 1 by the reference character 160, and is shown more in detail in Fig. 8. Mounted in connection with the underside of the work table 11 is a printing mechanism 161, the printing face 162 of which projects through an opening 162' in said work table 11, so as to lie substantially in the plane of the stock

strip supporting top surface of said work table. Journalized in and between bearing members 163, which upstand from the tops of the frame members 1 and 2 of the machine framework, is the pivoting 164 of a bell-crank lever comprising a dependent arm 165 and a forwardly extending horizontal arm 166 which overhangs the work table 11. Affixed to and extending between the tops of the frame members 1 and 2 of the machine framework is a bridge plate 167 by which is supported a dependent tubular guide member 168. Slidably reciprocable in said guide member 168 is a plunger rod 169 which is pivotally connected to the horizontal arm 166 of the bell-crank lever. Telescopically fitted on the lower end portion of the plunger rod 169, subject to axial movement thereon, is a platen 170. This platen is opposed to the printing mechanism 161. The axial movement of the platen 170 is limited by a pin and slot connection 171—172 by which the platen is coupled to the plunger rod. A compression spring 173, which is mounted between the platen and the lower end of the guide member 168, cushions the platen for upward yielding movement when said platen is brought into contact with the printing mechanism 161.

The bell-crank lever 165—166, with the platen 170, actuated thereby, is operated, in properly timed relation to the arrival and deposit of a stock strip between the printing mechanism 161 and the platen, by a cam 174 which is fixed on the main shaft 16. Said cam 174 engages an anti-friction roller 175 with which the free end of the dependent arm 165 of the bell-crank lever is provided. Pull spring means 176 causes the bell-crank lever to follow the actuating cam 174.

Beyond the station at which the stamping or printing operation is performed is the belt or strap body discharge station, at which station is located a longitudinal stop bar 180 (see Fig. 1), by which the belt or strap body, when advanced over the work table from the stamping station, is positioned at the discharge side of a work table subject to longitudinal propulsion for discharge therefrom, and thus from the machine. Located adjacent to the outer end of the work table in the path of discharge movement of a belt or strap body is the means for causing discharging propulsion of the belt or strap body. If desired, this propelling means may also be arranged to crease or score the side marginal portions of the face of the belt or strap body during discharge movement thereof. The propelling means (see Figs. 14 and 15) comprises an upper driving roll or rolls 181 fixed on a transverse driven shaft 182 which is journalized in and between bearing brackets 183 supported by the machine framework, and a lower bed roll 184 which is opposed to the driving roll or rolls 181. The driving roll or rolls may be of the smooth faced type if creasing and scoring action is not desired. If, however, scoring or creasing action is desired, a pair of suitably spaced apart scoring rolls having V-shaped peripheries as shown (again see Figs. 14 and 15) can be employed, and will serve both the scoring or creasing function as well as the propulsive discharge function. The means for actuating the driving roll or rolls 181 comprises a transverse countershaft 185 which is driven from the countershaft 28 by intermeshing gearing 186 (see Fig. 2). The shaft 182, by which the driving roll or rolls 181 is actuated, is driven from said countershaft 185 by chain and sprocket transmission 187. The bed roll 184 is supported for timed movement toward and from the driv-

ing roll or rolls 181; and to this end the shaft of the bed roll 184 is journalized in the horizontal arm 188 of a bell-crank lever which is pivotally supported in connection with the machine framework. The dependent arm 189 of this bell-crank lever is provided with an anti-friction roller 190. Journalized in bearing bracket means 191, which is supported by the machine framework below the work table 11, is a transverse shaft 192 that also is driven from the countershaft 185 by intermeshing gearing 193. On said shaft 192 is mounted an actuating cam 194 that is operative to engage the anti-friction roller 190 with which the dependent arm 189 of the bell-crank lever is provided. Pull spring means 195 causes the bell-crank lever to follow said actuating cam 194.

In the operation of the belt or strap body discharge means, as a belt or strap body is moved over the work table to the discharge station and there aligned by abutment against the stop bar 180, its outer end portion passes between the driving roll or rolls 181 and the bed roll 184, at which time said bed roll is lowered and thus separated from the driving roll or rolls, so that the interposed end portion of the belt or strap body is not engaged by the nip of these rolls. Thereafter the cam 194 is timed to actuate the bell-crank lever 188—189 whereby to lift the bed roll 184 toward the continuously rotating driving roll or rolls 181, thus nipping the interposed belt or strap body between these rolls, so that the driving roll or rolls, which rotate at relatively high speed, will thereupon grip and propel the belt or strap body outwardly through a discharge guide channel means 196, and thence out of the machine.

After a stock strip is deposited on the work table 11—12 at the receiving station, it is subject to engagement by automatic transfer means 40 by which it is moved transversely step by step, at properly timed intervals, from station to station to receive the processing treatment to be exercised thereon by the respective treating mechanisms which are located at the respective stations as above described. Said transfer means comprises a plurality of transversely extending belt or strap body propelling devices which are spaced apart along the work table surface. The number and spacing of said propelling devices is subject to variation, but, as shown, comprise 45 two in number, one mounted on the stationary work table 11 and the other on the movable work table section 12, although more than two thereof may be provided if desired. Said propelling devices being individually alike, detail description of one thereof will suffice. The propelling devices are generally indicated by the reference character 200.

Each propelling device (see Figs. 9 to 13 inclusive) comprises a stationary guide structure formed by upstanding, endwise open, guide frames 201 which are affixed to the work table respectively at the receiving side and the discharge side thereof. Provided in the sides of the guide frames 201 are internal slideway ledges 202, suitably spaced above the work table surface in plane parallel thereto, for the support of reciprocable impeller means. Affixed to and extending between the guide frames 201 are laterally spaced side members 203, the space intermediate thereof providing a slideway passage 204 in which the impeller means reciprocates. The impeller means comprises a slide member formed by laterally spaced apart slide bars 205 secured together by intermediate spacer members 206.

The slide bars 205 are slidably supported by the heretofore mentioned slideway ledges 202 with which the guide frames 201 are provided. Pivotally connected with and between the slide bars 205 are a plurality of bifurcate impeller members 207, the same being longitudinally spaced at suitable intervals along the slide member formed by said slide bars. Said impeller members 207 terminate at their lower free end portions in suitably shaped push fingers 208. Longitudinally movable between the slide bars 205 of the slide member is a tractor bar 209 which is straddled by the bifurcate impeller members 207, and to which the latter are also pivotally connected, subject to forward and back swing about the pivotal connections thereof to the slide member. Said tractor bar 209 has a lost motion coupled connection with the slide member that is provided by a stop member 210 which is affixed to the tractor bar, and which is provided with longitudinally spaced forward and rearward stop lugs 211 and 212 adapted to be engageable with a coupling cross-pin 213 that is affixed to and between the slide bars 205 of the slide member. The forward end portion of the tractor bar 209 extends freely beyond the forward end of the slide member and outwardly beyond the discharge side of the work table, and is adapted to be connected with means, to be presently described, for causing timed operative reciprocation of the propelling device.

Means is provided for varying the stroke of the propelling device, whereby to accommodate the same to stock strips of various widths. For narrow stock strips the propelling stroke, operative to transfer the stock strip from station to station, must be somewhat longer than would be required for transfer of wider stock strips, and consequently the stroke must be adjusted so that in either case the termination of the forward propelling phase thereof will dispose the stock strip in centrally aligned relation to the processing mechanisms at the respective station locations. The means for varying the stroke of the propelling device to such end comprises an adjustable stop member 214 which is threaded on a screw-threaded carrier shank 215; the latter projecting longitudinally outward from the rear end of the slide member of the propelling device. In operation, when properly adjusted on the carrier shank 215, the stop member 214 will abut the rear guide frame 201 so as to arrest the stock strip advancing stroke of the propelling device at a required predetermined point. The adjusted position of the stop member 214 for different widths of stock strips may be indicated by a suitably graduated scale provided on the periphery of said stop member so as to be readable with reference to a fixed indicator pointer 216 mounted on the rear guide frame 201 (see Figs. 9 and 10).

To cause properly timed reciprocation of the stock strip propelling devices, a rock-shaft 217 is journaled in bearing brackets 218, which project from the machine framework, to extend longitudinally along said machine framework adjacent to the discharge side of the machine. Mounted on this rock-shaft 217, so as to be oscillated thereby, are lever arms 219 adapted to be respectively coupled with the freely projecting end of the tractor bars 209 of the respective propelling devices. Each tractor bar 209 is coupled to a corresponding lever arm 219 by a yieldable coupling connection comprising a knuckle member 220 that is pivotally connected to the end of the tractor bar. Extending axially out-

ward from said knuckle member 220 is a tail rod 221 which slidably extends through a coupling collar 222 to which the lever arm 219 is pivotally connected. A compression spring 223 is mounted around the tail rod 221 between the coupling collar 222 and a stop nut 224 with which the end of the tail rod is provided. The yieldable coupling connection thus provided will accommodate the uniform oscillatory movement of the lever arm 219 to any variation in the stroke for which the propelling device is adjusted by the setting of the stop member 214. The means for producing properly timed oscillation of the rock-shaft 217 and its lever arms 219 comprises a cam 225 which is mounted on the outer end of the shaft 192 which is driven by the gearing 193 from the countershaft 185. Fixed on the rock-shaft 217 is a crank-arm 226 which is provided with an anti-friction roller 227 adapted to be engaged by the cam 225. A pull spring 228 is anchored to the machine framework and connected with a lever arm 229 fixed on the rock-shaft 217, whereby to cause the crank-arm 226 and its anti-friction roller 227 to follow the cam 225.

In the operation of each propelling device, the same, in its retracted normal initial position, is disposed to engage stock strips S which are supported by the work table so as to be located at the receiving and advance stations. After the processing operations, which are simultaneously performed at advance stations, are completed, the means by which the propelling device is actuated is timed to effect an advance stroke of said propelling device. Such advance stroke is produced by outward swing of the lever arm 219 by which the propelling device is reciprocated. As outward swing of the lever arm 219 is initiated, the first effect is to induce an initial independent longitudinal movement of the tractor bar 209 which is permitted by the above described lost motion connection of said tractor bar with the slide bars 205 of the slide member. The effect of this initial movement of the tractor bar 209 is to down swing the impeller members 207, whereby to engage their push fingers 208 behind the stock strips S. This having occurred, the rearward stop lug 212 of the lost motion coupling connection engages the cross-pin 213 of the slide member, whereupon said slide member accompanies continued advancing movement of the tractor bar 209, and consequently causes the impeller members 207 to slide the stock strips S over the work table from one station to a next succeeding station (see Fig. 9). To hold the stock strips S against displacement from aligned relation to processing mechanisms located at stations to which the stock strips have been thus delivered, bowed detent spring members 230, which are affixed to the under edges of the side members 203 of the guide structure in which the slide member moves, tensionally bear upon the delivered stock strips S, whereby to frictionally bind the same to the work table surface (see Figs. 9 and 10). While the processing mechanisms at the advance stations are performing their functions, the means by which the propelling device is actuated is timed to effect the return or recovery stroke of the propelling mechanism, which is effected by inward swing of the lever arm 219 by which the propelling device is reciprocated. As inward swing of the lever arm is initiated, the first effect is to induce an initial inward longitudinal movement of the tractor bar 209, which functions to

swing up the impeller members 207 so that the push fingers 208 will clear the deposited stock strips S (see Fig. 10). This having occurred, the forward stop lug 211 of the lost motion coupling connection engages the cross-pin 213 of the slide member, whereupon the slide member accompanies continued retractive movement of the traction bar 209, whereby to return the propelling device to its retracted normal initial position, ready for repetition of the above described operative reciprocation thereof.

The movable frame member 4 and work table section 12 connected therewith, together with associated mechanisms, are longitudinally adjustable on the machine framework relative to the stationary frame members 1-2, work table 11 and mechanisms associated therewith. Such permitted adjustment accommodates the processing mechanisms for operation upon stock strips S of various length size. To this end, the machine framework is provided, within respective sides thereof, with longitudinally disposed rail bars 240 which are affixed to and extend between the stationary frame members 2 and 3 of the machine framework. The movable frame member 4 is slidably supported by said rail bars 240 for movement toward and from the stationary frame members 1-2 and mechanisms associated therewith. Means is provided for effecting adjusting movements of the movable frame member 4 and mechanisms supported thereby, including the propelling device associated with the work table section 12 which is carried by said movable frame member 4. The means for this purpose comprises rotatable adjusting screws 241 which respectively extend along respective sides of the machine framework, and which are journaled in and between supporting bearings 242 respectively affixed to the stationary frame member 2 and the stationary frame member 3. Secured to opposite sides of the movable frame member 4 are respective internally screw-threaded traveler members 243 which are respectively engaged by the respective adjusting screws 241. On the outer end of one of the adjusting screws 241 is secured a hand wheel 244 by means of which the same can be rotated in direction to effect selected adjusting movement of the movable frame member 4, work table 12 and associated mechanisms. To obtain simultaneous rotation of both adjusting screws 241, the rotation of the manipulated adjusting screw is transmitted to the other adjusting screw by interconnecting chain and sprocket transmission 245. If, by outward adjustment, the work table section 12 is separated from the stationary work table 11, the gap therebetween may be closed by insertion of one or more removable table leaves (not shown) adapted to be supported by the machine framework.

The lay shaft 68, the lay shaft 136 and the rock shaft 217 are preferably provided with splines 246 to permit the driving cams or parts keyed thereto for operation thereby to adjust themselves thereon in correspondence to the adjusted position of the movable frame member 4, work table section 12 and associated mechanisms. The cam 16, which actuates the stock strip centering device which cooperates with the mechanism carried by the movable frame member 4 for shaping and punching the free end portions of the stock strips, can be conformingly adjusted on the main shaft 16.

It may be here pointed out that for the upper feed roll 23 may be substituted a pair of laterally

spaced scoring rolls, such as the scoring rolls 181, whereby the in-feeding of a stock strip onto the work table for deposit at the receiving station thereof is accompanied by the scoring or creasing of the face of the stock strip. In such case, the discharge roll cooperative with the discharge station of the work table would be of a smooth and preferably resilient face type. In other words, the scoring or creasing operation, if desired to be performed, may be optionally carried on at either the work input point or the work output point of the machine.

It is believed that the operation of the machine as a whole, whereby stock strips delivered into the machine and deposited on the work table thereof are automatically moved step by step over the work table subject to successive desired processing operations to convert the same into belt or strap bodies which are finally discharged from the machine, will be understood from the above detailed description of the machine and its processing mechanisms without further repetition or amplification.

Having now described my invention, I claim:

1. In a machine for processing stock strips to produce belt or strap bodies therefrom wherein a plurality of work treating stations, at which are performed various processing operations, are spaced apart across a work supporting table between a work receiving station and a work discharge station; the combination with said table of automatic means for moving the work from station to station subject to the processing operations, said work moving means comprising a plurality of parallelly spaced guide structures mounted on and above the work supporting table to extend across the same, longitudinally reciprocable work propelling devices respectively slideable in the respective guide structures, each propelling device comprising a slide member having pivoted impeller members spaced therealong, said impeller members being oscillatable in plane perpendicular to the plane of said work supporting table toward and from the latter, a tractor bar intermediate the work supporting table and said slide member to which said impeller members are pivotally connected to swing the same to and from work engaging positions, a lost motion connection between the slide member and tractor bar whereby after initial impeller member positioning movement of the latter continued movement thereof is transmitted to the slide member, said lost motion connection comprising a stop member affixed to the tractor bar having longitudinally spaced forward and rearward upstanding stop lugs and a cross-pin carried by said slide member subject to engagement by said stop lugs, and means to effect timed reciprocation of the work propelling devices.

2. In a machine for processing stock strips to produce belt or strap bodies therefrom wherein a plurality of work treating stations, at which are performed various processing operations, are spaced apart across a work supporting table between a work receiving station and a work discharge station; the combination with said table of automatic means for moving the work from station to station subject to the processing operations, said work moving means comprising a plurality of parallelly spaced guide structures mounted on and above the work supporting table to extend across the same, longitudinally reciprocable work propelling devices respectively slideable in the respective guide structures, each propelling device comprising a slide member having

pivoted impeller members spaced therealong, said impeller members being oscillatable in plane perpendicular to the plane of said work supporting table toward and from the latter, a tractor bar intermediate the work supporting table and said slide member to which said impeller members are pivotally connected to swing the same to and from work engaging positions, a lost motion connection between the slide member and tractor bar whereby after initial impeller member positioning movement of the latter continued movement thereof is transmitted to the slide member, said lost motion connection comprising a stop member affixed to the tractor bar having longitudinally spaced forward and rearward upstanding stop lugs and a cross-pin carried by said slide member subject to engagement by said stop lugs, a rock-shaft, lever arms oscillated by the rock-shaft, a yieldable coupling connection between the free ends of the lever arms and the outer ends of the tractor bars of the work propelling devices, and means operative to cause timed oscillation of the rock-shaft.

3. In a machine for processing stock strips to produce belt or strap bodies therefrom wherein a plurality of work treating stations, at which are performed various processing operations, are spaced apart across a work supporting table between a work receiving station and a work discharge station; the combination with said table of automatic means for moving the work from station to station subject to the processing operations, said work moving means comprising a plurality of parallelly spaced guide structures mounted on the work supporting table to extend across the same, longitudinally reciprocable work propelling devices respectively slidable in the respective guide structures, each propelling device comprising a slide member having pivoted impeller members spaced therealong, a tractor bar pivotally connected with the impeller members to swing the same to and from work engaging positions, a lost motion connection between the slide member and tractor bar whereby after initial impeller member positioning movement of the latter continued movement thereof is transmitted to the slide member, a rock-shaft, lever arms oscillated by the rock-shaft, a yieldable coupling connection between the lever arms and the tractor bars of the work propelling devices, means operative to cause timed oscillation of the rock-shaft, and means for regulating the work propulsion stroke of the propelling devices to accommodate the same to various widths of work, said latter means comprising a screw-threaded carrier shank projecting axially rearward from the slide member of each propelling device, and a stop member threaded on each carrier shank for adjustment thereon, said stop members being adapted to abut the rearward ends of the guide structures which support the slide members whereby to arrest forward movement of the latter so as to predetermine the work advancing strokes thereof.

4. In a machine for processing stock strips to produce belt or strap bodies therefrom wherein a plurality of work treating stations, at which are performed various processing operations, are spaced across a work supporting table between a work receiving station and a work discharge station; a table framework, said framework having an upstanding stationary frame structure to support parts of work treating mechanisms at respective work treating stations and an upstanding movable frame structure to support other cooperative parts of work treating mecha-

nisms at corresponding respective work treating stations, means for adjusting said movable frame structure toward and from the stationary frame structure, whereby to position the cooperative work treating mechanisms for operation upon work of various length sizes, automatic means cooperative with said table for moving the work across the table from station to station subject to the processing operations of there located treating mechanisms, said work moving means comprising a plurality of parallelly spaced guide structures mounted on the work supporting table to extend across the same intermediate said stationary and movable frame structures, longitudinally reciprocable work propelling devices respectively slidable in the respective guide structures, each propelling device comprising a slide member having pivoted impeller members spaced therealong, a tractor bar pivotally connected with the impeller members to swing the same to and from work engaging position, a lost motion connection between the slide member and tractor bar whereby, after initial impeller member positioning movement of the latter, continued movement thereof is transmitted to the slide member, and means to effect timed reciprocation of the work propelling devices.

5. In a machine for processing stock strips to produce belt or strap bodies therefrom wherein a plurality of work treating stations, at which are performed various processing operations, are spaced across a work supporting table between a work receiving station and a work discharge station; a table framework, said framework having an upstanding stationary frame structure to support parts of work treating mechanisms at respective work treating stations and an upstanding movable frame structure to support other cooperative parts of work treating mechanisms at corresponding respective work treating stations, means for adjusting said movable frame structure toward and from the stationary frame structure, whereby to position the cooperative work treating mechanisms for operation upon work of various length sizes, automatic means cooperative with said table for moving the work across the table from station to station subject to the processing operations of there located treating mechanisms, said work moving means comprising a plurality of parallelly spaced guide structures mounted on the work supporting table to extend across the same intermediate said stationary and movable frame structures, longitudinally reciprocable work propelling devices respectively slidable in the respective guide structures, each propelling device comprising a slide member having pivoted impeller members spaced therealong, a tractor bar pivotally connected with the impeller members to swing the same to and from work engaging position, a lost motion connection between the slide member and tractor bar whereby, after initial impeller member positioning movement of the latter, continued movement thereof is transmitted to the slide member, and means to effect timed reciprocation of the work propelling devices.

6. In a machine for processing stock strips to produce belt or strap bodies therefrom wherein a plurality of work treating stations, at which

are performed various processing operations, are spaced across a work supporting table between a work receiving station and a work discharge station; a table framework, said framework having an upstanding stationary frame structure to support parts of work treating mechanisms at respective work treating stations and an upstanding movable frame structure to support other cooperative parts of work treating mechanisms at corresponding respective work treating stations, means for adjusting said movable frame structure toward and from the stationary frame structure, whereby to position the cooperative work treating mechanisms for operation upon work of various length sizes, automatic means cooperative with said table for moving the work across the table from station to station subject to the processing operations of there located treating mechanisms, said work moving means comprising a plurality of parallelly spaced 20 guide structures mounted on the work supporting table to extend across the same intermediate said stationary and movable frame structures, longitudinally reciprocable work propelling devices respectively slidably in the respective guide structures, each propelling device comprising a slide member having pivoted impeller members spaced therealong, a tractor bar pivotally connected with the impeller members to swing the same to and from work engaging positions, a lost motion connection between the slide member and tractor bar whereby, after initial impeller member positioning movement of the latter, continued movement thereof is transmitted to the slide member, and means to 30 effect timed reciprocation of the work propelling devices, comprising a longitudinal rock-shaft supported in connection with the table framework, lever arms oscillated by the rock shaft, a yieldable coupling connection between the lever arms and the tractor bars of the work propelling

10
15

5 devices, means operative to cause timed oscillation of the rock shaft, means for regulating the work propulsion stroke of the propelling devices to accommodate the same to various widths of work, said latter means comprising a screw-threaded carrier shank projecting axially rearward from the slide member of each propelling device, and a stop member threaded on each carrier shank for adjustment thereon, said stop members being adapted to abut the rearward ends of the guide structures which support the slide members, whereby to arrest forward movement of the latter so as to predetermine the work advancing strokes thereof.
